UNITED STATES PATENT OFFICE

2,605,834

PERFORATING GUN FOR WELL CASINGS

James O. Tow, Huntington Park, Calif., assignor
to McCullough Tool Company, Vernon, Calif.,
a corporation of Nevada

Application January 6, 1948, Serial No. 715

3 Claims. (Cl. 164—0.5)

1

My invention relates to guns of the kind used for perforating well casings by shooting projectiles therethrough.

The objects of my invention are, first, to provide a perforating gun that is of simple construction and economical to make; second, to make efficient use of the propellant and to so achieve great perforating ability with a relatively small quantity of propellant material; third, to make close spacing of shots practical in a hard shooting gun; and fourth, to provide for safe and easy loading of the gun.

The invention is illustrated in the accompanying drawing in which, Fig. 1 is a vertical sectional view of a preferred form of my invention; and Fig. 2 is a horizontal section taken on the line 2—2 of Fig. 1.

With reference to Figures 1 and 2 the construction is as follows:

A cylindrical body 10 has one or more bores 11, which are defined by cylindrical walls 15, and end walls 13. The axis of each bore 11 preferably intersects the axis of the body 10 at 90°.

The body 10 has a fire hole 12, the axis of which preferably coincides with the axis of the body and so (preferably) intersects the axis of each of the bores 11.

At its upper end the fire hole 12 terminates in a chamber 21 defined by the wall 14. The body 10 is provided at its upper end with a threaded box 20 adapted to receive a sub of more or less standard design and not here shown as it is not a part of this invention. This sub may be one of types in general use—one which is affixed to a wire rope which rope is used for lowering the gun into the well and withdrawing it therefrom. This sub is adapted to receive a primer used in firing the gun, and which primer is fired electrically or mechanically. The gun when assembled for shooting consists of the body 10, the primer charge 19, ordinarily of gun powder and which is placed in the chamber 21; the propellant charges 16 of gun powder or other suitable explosive; the projectiles 17 of steel or other suitable material; and the seals 18, ordinarily of rubber.

In loading a bore 11 the propellant charge 16 is placed in the bore and against the wall 13, and the projectile is placed in the bore against the propellant charge as shown; then the seal is pushed into place against the projectile as shown.

In my invention it is essential that the projectile when in firing position covers the junction of the fire hole with the bore 11. This placement of the projectile to cover the junction of the fire hole with the bore is an important part of my

2

invention. This position of the projectile substantially seals off the propellant from any void cavity until the projectile has moved forward to uncover the junction of the fire hole with the bore.

Since in practice the diameter of the projectile is made slightly less than the diameter of the bore (so that there is a loose fit) there is a flash-back of fire or hot gas between the projectile and the bore wall to the propellant, sufficient to ignite the propellant, when the primer is ignited and fire or hot gas therefrom is forced down the fire hole against the first projectile.

As the first projectile is fired and uncovers the juncture of the fire hole with the bore, fire or hot gas is forced down the fire hole to the second projectile and the firing process continues and so on until all of the projectiles have been fired. When the pressure of gas from ignition of the primer or propellant comes to bear on the upper side of a projectile, it forces the projectile against the lower wall of the bore, thus increasing the clearance between the upper side of the projectile and the upper wall of the bore. This pressure against the upper side of the projectile tends to lock the projectile to some extent against movement until ignition of the propellant has begun.

When the sub used with this gun (and which screws into box 20) is provided with a sufficiently powerful primer, the primer 19 may be eliminated. If desired, several guns embodying this invention may be joined together end to end by providing a suitable threaded pin on the lower end of the gun body, and by continuing the fire hole through to the bottom of the gun. When used singly the fire hole can be plugged with a screw at the bottom of the gun and a bull nose guide screwed on to the pin.

Having thus described my invention I claim:

1. In a perforating gun of the character described, the combination of a body having a plurality of bores extending transversely into said body and a longitudinally extending fire hole of restricted cross section communicating with said bores, projectiles in said bores in positions to cover junctions of said fire hole with said bores, propellant charges filling said bores behind said projectiles, said projectiles being so formed with relation to the walls of said bores as to provide a passageway for passage of hot gases from said fire hole to said propellant charges, and a primer charge in communication with said fire hole in such position that hot gases proceed sequentially from one to another of said bores in the order of their arrangement along the fire hole.

2. A perforating gun as defined in claim 1, having seals in front of said projectiles.

3. In a perforating gun, the combination of a body, a plurality of laterally extending bores in said body, said bores being closed at their inner ends, a longitudinally extending fire hole of restricted cross-section intersecting each of said bores between the ends of the bores, a perforating projectile in each of said bores in position to cover the fire hole, a propellant charge filling each of said bores between the inner end of the projectile and the closed inner end of the bore, and a primer charge in communication with said fire hole adjacent one end thereof, said projectiles permitting flame from said fire hole to pass be- 15

tween the projectiles and the walls of their respective bores to their respective propellant charges.

JAMES O. TOW.
